UNITED STATES PATENT OFFICE.

ROMAN J. SIODLA, OF BEREAL, OHIO.

SHOCK-ABSORBING SPRING CLIP.

Application filed September 14, 1926. Serial No. 135,372.

The present invention relates to means for automatically increasing the strength of a spring or its resistance to flexure as the spring is flexed in one or both directions 5 from its normal position by reason of increased weight or some pressure being applied on the spring.

The invention is especially applicable when a pressure is suddenly applied, tending to very quickly flex the spring and also when said pressure is suddenly relieved to prevent the sudden re-action or rebound of the spring, producing violent swinging of the supporting member.

15 The invention is applicable to any use where it is desired to support the end of the leaves of the spring. The invention is applicable to all vehicles using the common springs but, of course, is designed more particularly for automobiles.

20 Another very important object of the invention lies in the provision of a device of this nature which is exceedingly simple in its construction, strong and durable, inexpensive to manufacture, and efficient and reliable in use, not likely to easily become out of order, easy to apply, and otherwise well adapted to the purpose for which it is designed.

25 30 With the above and numerous other objects in view as will appear as the description proceeds, the invention resides in certain novel features of construction, and in the combination and arrangement of parts 35 as will be hereinafter more fully described and claimed.

In the drawing:—

Figure 1 is an elevation of the device embodying the features of my invention, 40 Fig. 2 is an other elevation thereof, taken at right angles to that shown in Fig. 1,

Fig. 3 is a similar elevation to that shown in Fig. 2, but showing the device applied, and

45 Fig. 4 is an elevation shown in Fig. 1, but illustrating a modified form.

Referring to the drawing in detail, and particularly the embodiment shown in Figs. 1 to 3 inclusive, it will be seen that 5 50 denotes a bar which is provided with counter-sunk openings 6, the counter-sunk portions of which are indicated specifically by the

numerals 7 and are grounded for receiving the heads of the bolts 8 which project thru the openings 6. The numeral 9 denotes a 55 curved spring bar which is provided with openings 10 through which the bolts 8 project. These bolts 8 are provided with spring washers 11 and nuts 12 so that the spring bar 9 may be disposed above the group of 60 springs while the bar 5 is disposed below the group of springs.

By referring to Fig. 3, an application of the invention will be seen, wherein it will be noted that the structure is disposed about the ends of the leaves of the spring, preferably the upper three or four. The device tends to clamp these ends together so as to particularly resist rebounds, which tends to throw the body of the vehicle upwardly 70 after the spring has been violently compressed by an obstacle, ditch, or some other like roughness in the road.

It is to be noted that the undersurface of the spring plate 9 and the upper surface of the plate 5 are convexed. In Fig. 4, another embodiment of the invention has been illustrated wherein the plate 5' is provided with openings 6' and a single U-bolt 8' is used that projects through the openings 6'. 80 Otherwise this embodiment of the invention is identical with that previously described, and is used in the same manner.

From the above description, it will be seen that I have devised an exceedingly simple 85 device for absorbing shocks in a motor vehicle. The device is capable of being easily placed upon the semi-elliptical springs now in common use, and will effectively eliminate the rebounds which cause occupants to leave their seats and make the vehicle ride very uncomfortably on a rough road. The device is very inexpensive and yet will prove strong and durable besides having the desired efficiency.

90 The present embodiment of the invention has been disclosed in detail by way of example, since in actual practice it attains the features of advantage enumerated as desirable in the statement of the invention and the above description. It will be apparent that slight changes in the details of construction and in the combination and arrangement of parts may be resorted to with-

out departing from the spirit or scope of the invention as hereinafter claimed, or sacrificing any of its advantages.

Having thus described my invention, what 5 I claim as new is:—

A device of the class described including a straight plate having a pair of end openings, a bowed spring bar having a pair of end openings, said bowed plate being spaced

from the straight plate to receive a spring 10 therebetween, bolts projecting through the openings, nuts on the bolts to draw the plate and bar towards each other, the opposed faces of the plate and bar abutting the spring being convex transversely. 15

In testimony whereof I affix my signature.

ROMAN J. SIODLA.
